UNITED STATES PATENT OFFICE.

EDGAR C. VEAZEY, OF WEST POINT, VIRGINIA.

TOBACCO-FURNACE.

1,359,550.

Specification of Letters Patent. Patented Nov. 23, 1920.

Application filed December 15, 1919. Serial No. 344,812.

To all whom it may concern:

Be it known that I, EDGAR C. VEAZEY, a citizen of the United States, residing at West Point, in the county of King William 5 and State of Virginia, have invented a new and useful Tobacco-Furnace, of which the following is a specification.

The device forming the subject matter of this application is a tobacco barn furnace 10 and one object of the invention is to provide a device of the sort above alluded to embodying a casing adapted to receive air and direct the air upwardly about that portion of the furnace in which combustion takes 15 place, novel means being provided for directing the heated air laterally.

Another object of the invention is to provide novel means for assembling the casing which directs the air upwardly and laterally, with the body portion of the furnace. 20

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 30 and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention, a portion of the wall of the tobacco barn appearing in section; Fig. 2 is a vertical longitudinal section of the structure shown in Fig. 1; Fig. 3 is a front elevation of the structure depicted in Fig. 1; and Fig. 4 is a transverse section showing the furnace.

The device forming the subject matter of this application comprises a furnace including a bottom 1 having upstanding flanges 2 connected by securing elements 3 with the sides 4 of the arched body 5 of the furnace, the lower edges of the sides being received 45 within the flanges 2 and resting on the bottom 1. The furnace includes a rear end wall 6 provided with a nipple 7 adapted to receive a flue 10. The rear end wall 6 of the furnace body is supplied with a flange 8 located on the outside of the part 5 and 55 connected thereto by securing elements 9. The furnace includes a front frame 11 having a flange 12 extended within the body 5 and connected thereto by securing devices 14, the frame having an opening 15 controlled by a door 16 mounted on hinges 17 and adapted to be held closed by a latch 18, the door carrying a damper 19 of any desired construction. A grate 20 is located in the furnace body 5 and may be constructed as desired, depending upon the nature of the fuel used. The grate may have legs 21 coöperating with the bottom 2 to space the grate from the bottom. 60

Laterally extended U-shaped supports 22 are provided, the upper ends 23 of the supports 22 being connected by securing members 24 to the top portion of the furnace body 5. The lower ends 25 of the supports 22 extend inwardly and are provided with 75 extensions 26 overlapped upon the flanges 2 of the bottom 1, and connected to the said flanges and to the sides 4 of the furnace body 5 by certain of the securing elements 3.

The invention includes a casing having 80 sides 27 spaced from the sides 4 of the furnace body 5 and connected by securing elements 28 to the intermediate portions of the laterally extended U-shaped supports 22. The lower ends of the sides 27 of the casing 85 are fashioned into outwardly extended, upwardly inclined deflecting flanges 29. The casing includes an end 30 having a flange 31 overlapped upon the outside of the furnace body 5 and connected thereto by securing elements 32. The flue 10 projects through the end 30 of the casing. At its lower end, the member 30 of the casing is supplied with an outwardly extended upwardly inclined deflecting flange 33, complementary to the flanges 29 on the sides 27 of the casing. Reinforcing strips 34 extend upwardly along the inner surface of the sides 27 of the casing, at the ends thereof these parts being held to the sides of the casing by certain of the securing elements 32. The upper ends of the reinforcing strips 33 are inwardly inclined, as indicated at 35, and are secured at 36 to a deflector 37, in the form of a plate, the deflector being spaced 90 from the upper edges of the sides 27 on the casing, and from the upper edge on the end 30 of the casing. The sides 27 of the cas- 95

100

105

ing converge as they extend upwardly, as shown in Fig. 4, the sides of the casing being reversely curved adjacent their upper edges, and terminating at their upper edges, 5 in approximately parallel portions.

The numeral 38 denotes a wall of a tobacco barn. The furnace body 5 projects through the wall 38 of the barn, and the open end of the casing abuts against the wall of the 10 barn, as indicated clearly in Fig. 1 of the drawings.

In practical operation, a fire is built within the furnace body 5, the products of combustion escaping by way of the flue 10, the 15 flue 10 being disposed within the tobacco barn in accordance with any of the established practices resorted to by tobacco planters. The relatively cool air adjacent the floor of the barn passes beneath the inclined deflecting members 29 and 33 and flows upwardly within the casing 27-30. The air is held by the casing in relatively close relation to the body 5 of the furnace and is heated thereby, the air passing upwardly out of the open top of the casing. Heated air impinges against the upper deflecting plate 37 and is carried laterally thereby, the air thus being diffused in the 25 tobacco barn.

30 The structure forming the subject matter of this application affords a simple means whereby the air may be drawn from a point adjacent the bottom of the tobacco barn, and be heated, the heated air being delivered into the barn and being diffused therein. Further, the invention discloses a simple means whereby the various parts of the 35 device, such as the body 5, the parts of the casing, and the deflecting plate 37, may be

held together to form a strong and operative structure.

Having thus described the invention, what is claimed is:—

1. In a device of the class described, a furnace; an exterior casing reduced in width 45 at its top and having an opening in its top, the opening extending upbrokenly from one end of the casing to the other, one end of the furnace projecting beyond the corresponding end of the casing, the other end 50 of the furnace being disposed within the casing, the extreme lower edge of the casing being disposed above the lower edge of the furnace and said edge being provided with an outwardly extended upwardly inclined flange; a baffle supported on the casing and located above the opening in the top of the casing; and a wall constituting a closure for the space between the first specified end of the casing and the furnace. 60

2. In a device of the class described, a furnace; a casing open at the top and inclosing the furnace; outwardly extended supports having their ends attached to the furnace and having their intermediate portions attached to the casing; reinforcing strips secured to the side portions of the casing and extended above the casing; and a deflector carried by the upper ends of the strips, in spaced relation to the top of the casing. 70

In testimony that I claim the foregoing as my own, I have hereto affixed my signature in the presence of two witnesses.

EDGAR C. VEAZEY.
